CAN PUNCH

George D. McNeill, Selma, Calif.

Continuation of application Serial No. 668,961,
May 2, 1933. This application November 28,
1933, Serial No. 700,061

7 Claims. (Cl. 164—119)

This invention relates to a device for punching holes in cans, such as those in which condensed milk, fruit juice and the like are marketed, and in which the liquid is kept after the can is opened and poured therefrom through the punched holes as needed. The present application is also a continuation of my co-pending application for patent, Serial No. 668,961, filed May 2, 1933.

The principal object of my invention is to provide a device for this purpose by means of which a pair of opposed holes may be easily and neatly punched in the can with one operation and which is adjustable to different sized cans, so that the holes will always be near the rim, by the mere act of placing the device on the can and without the need of any adjustment screws or other parts requiring manual manipulation to make such adjustment.

Another object of the invention is to provide a device for the purpose so constructed that the act of placing the same on the can and punching the holes may be carried out with one hand and with a practically continuous operation.

A still further object is to provide a can punch so constructed that the punching elements are normally concealed and protected so that they cannot damage the hands or other exterior objects or themselves become damaged or bent from exposure and contact with relatively unyielding objects.

These objects I accomplish by means of such structure and relative arrangement of parts as will fully appear by a perusal of the following specification and claims.

In the drawing similar characters of reference indicate corresponding parts in the several views.

Figure 1 is a side view of the device in its normal contracted position shown as being placed on a can.

Figure 2 is a sectional elevation of the device, shown in position on the can and with the punches depressed.

Figure 3 is a fragmentary cross section on the line 3—3 of Figure 1.

Referring now more particularly to the characters of reference on the drawing, the base structure of the device comprises a strip 1 on which is slidably superimposed another and somewhat narrower strip 2, one end of the strip 1 normally extending beyond the adjacent end of the upper strip and the other end of said upper strip extending beyond the corresponding end of the lower strip, as shown in Figure 1. Said corresponding end of the strip 1 carries a depending jaw 3 to engage the adjacent side of a can 4,

while the opposite end of the upper strip 2 carries a similar jaw 5 to engage the opposite side of the can. The last named jaw depends through a longitudinal slot 6 cut in the adjacent portion of the under strip 1.

The strip 2 is slidably guided on the strip 1 by longitudinally spaced guide lugs 7 having appropriate side recesses and mounted on said strip 1 to the sides of the strip 2. The strips are normally held in contracted relationship by a tension spring 8 extending between one of said lugs and another lug 9 mounted on the strip 2; in which position of the strips the jaws are closer together than the diameter of the smallest can. The strips however can separate so that the jaws will be spread apart a distance greater than the diameter of the largest can, so that one device may be used with all sizes of cans in which milk or juice is marketed.

Projecting upwardly from and rigidly mounted on the strip 1 is a post 10, while spaced lengthwise therefrom is another post 10a secured in the strip 2. A depressor plate 11 disposed parallel to the strips 1 and 2 is slidable on the posts, said depressor plate having a longitudinal slot S in which the post 10 rides. Pointed punch stems 12 and 13 disposed parallel to and on opposite sides of the posts are slidable in sleeves 14 and 15 respectively. The sleeve 14 projects through a longitudinal slot 16 in the strip 2 (and through which the post 10 also projects) and is rigidly secured to the lower strip 1, while the sleeve 15 is secured to the upper strip 2. The punches are thus mounted in connection with the relatively movable strips and are so positioned with respect to the corresponding jaws as to engage the can adjacent its rim when the jaws are engaged with the outside of the same, as shown in Figure 2.

The stems 12 and 13 have enlarged heads 17 and 18 respectively on their upper ends and bearing against the plate 11. Compression springs 19 and 20 extend between the heads 17 and 18 and the strips 1 and 2 respectively and are disposed about the corresponding sleeves. These springs act to force the stems and plate 11 upwardly so that the sharp punching points of the stems will be normally disposed above the bottom surface of the lower strip 1 as shown in Figure 3 and hence will be protected from damage and prevented from causing any damage.

The plate 11 being longitudinally immovable relative to the strip 2 on which the stem 13 is mounted, the head 18 of said stem always bears against said plate at the same point. The stem 12 being mounted on the strip 1 which is slidable

110

relative to the strip 2 and plate 11, the head 17 of said stem changes position on the strip 11 with the sliding movement of said strip. The plate 11 is consequently long enough at the corresponding 5 end to allow for the full separating movement of the strips while still retaining the head 17 engaged with said plate.

To depress the plungers against the resistance of the springs 19 and 20 and cause the punch 10 stems to project below the bottom strip and through the top of the can, I preferably provide the following means:

Formed on the upper ends of the posts 10 and 15 10a and extending lengthwise of the plate 11 in opposite directions from each other are hook-like heads 21. Separate handles 22 spaced lengthwise of the device are disposed above the plate 11 at a normally diverging angle to each other. The handles at their lower ends are 20 formed with flat angularly set cam members 23 disposed under the heads 21, the latter having depending tips 24 at their outer ends normally engaging the plate 11. The handles are provided with slots 26 adjacent their lower end through 25 which the posts project. The lower edges of the cams joins the inner edges of the handles with a curve of relatively short radius as indicated at 27, said curved edge riding on the plate 11. The tips 24 prevent the handles from being unintentionally pulled out from place at any time.

As a result of this arrangement the punch stem springs normally act to turn the cams so that their flat end portions are in contact with the plate 11 and in close relationship to the heads 21. 30 This limits the upward movement of the plate 11 and causes the handles to be disposed at an angle of considerable divergence to each other, as shown in Figure 1. When the handles are drawn together the ends of the cams are tilted upwardly 35 so as to engage the corresponding heads and the curved surfaces 27 of said cams come in contact with the plate 11 depressing the same, as shown in Figure 2.

To use the device the can is held in one hand 40 and the device in the other, preferably with the jaw 3 facing the hand and with the adjacent end of the strip 2 engaged with the palm of the hand near the ball of the thumb, while the fingers and thumb extend along and above the strip 11 to engage the handles near the base. Very little 45 practice will enable the operator to thus grasp the device in a comfortable manner and one which makes it very easy to operate the implement. The device is then initially placed on the can so that the jaw 3 engages the same on one side, as 50 shown in Figure 1. A relatively slight hand pressure against the strip 2 is sufficient to slide the same along the strip 1 so that the jaw 5 will be moved across the can whatever distance is 55 necessary to cause said jaw to extend to and engage the opposite side of the can, and which distance of course depends on the size of the can being used.

The pressure on the strip 2 is then released and 60 the device becomes automatically clamped to the can by the jaws and by the pressure of the spring 8 tending to pull said jaws together. A very slight upward shifting of the hand then enables the fingers to have the proper grip on the handles and the closing of the hand causes said handles to be drawn together, as shown in Figure 2, thus depressing the punches through the can in the manner previously explained. The leverage obtained by the handles and cam construction 65 makes the punching operation extremely easy so

that the hardest tin may be penetrated with a very weak force applied to the handles. Upon the pressure on the handles being released the springs 19 and 20 immediately act to raise the punches and the device may be withdrawn from the can by a slight advancing pressure on the strip 2 accompanied by an upward tilting of the opposite end of the device.

It will be obvious that the downward pressure of the punches against the top of the can tends to cause the base strips 1 to 2 to move upwardly. Such movement can only take place to a very limited extent, or until the ends of the jaws engage the under edge of the rim 4a of the can, as shown in Figure 2, since the spring 8 is exerting a constant pull on the jaws, there is no tendency for them to climb from such rim engaging position, and the device is thus effectively held on the can while the punching operation is performed. The posts, being mounted in fixed connection with respect to the relatively movable strips and punches, move apart as the punches are spread so that the point of pressure application of the cams relative to the punches always remains the same.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. A can punch comprising superimposed strips, means connecting said strips together for relative longitudinal sliding movement, a jaw to engage the side of a can depending from one end of one strip and a similar jaw depending from the opposite end of the other strip, punches mounted on the strips adjacent their respective jaws for vertical movement relative thereto, means to normally hold the punches clear of the lower strip, a plate fixed in connection with one strip and engaging the upper ends of the punches, and means to depress the plate at will.

2. A can punch comprising superimposed strips, means connecting said strips together for relative longitudinal sliding movement, elements to engage a can on its opposite sides depending from the opposed ends of the strips, sleeves fixed on and upstanding from the strips separately and inwardly of the respective elements, punch stems slidable in the sleeves, springs acting on the stems to normally hold their lower ends clear of the lower strip, and means to depress both stems simultaneously against the resistance of the springs.

3. A device as in claim 2 in which said second means comprises a plate fixed in connection with one strip and engaging the upper ends of the stems, and means to depress the plate.

4. A can punch comprising a base structure having opposed jaws depending therefrom to engage a can on its opposite sides, posts fixed on and upstanding from said structure, a plate slideable on said posts, vertical punch stems slidably mounted on the structure and engaging the under side of the plate, springs yieldably holding the stems against the plate, and means to depress the plate against the stems.

5. A device as in claim 4, in which said means comprises normally diverging handles above the plate, plate engaging cams depending from the handles, and cam engaging means on the posts 5 above the plate and arranged, with said cams, to cause a drawing together of the handles to turn the cams so as to depress the plate.
6. A can punch comprising superimposed strips, means connecting said strips together for 10 relative longitudinal sliding movement, a jaw to engage the side of a can depending from one end of the lower strip and a similar jaw depending from the opposite end of the upper strip, the lower strip having a longitudinal slot through 15 which the last named jaw projects, a sleeve fixed on and upstanding from the lower strip adjacent its jaw, the upper strip having a longitudinal slot through which the sleeve projects, another sleeve fixed on and upstanding from the upper strip adjacent its jaw, punch stems slidable in the sleeves, and projecting from the upper end thereof, a plate above the stems parallel to the strips, means mounting said plate in connection with the upper strip for vertical movement relative thereto, springs acting to hold the upper ends of 20 the stems against the plate, plate depressing 25 handles above the plate, and means mounting said handles in connection with the plate mounting means to limit the movement of the handles in a plate releasing direction.
7. A can punch comprising superimposed strips, means connecting said strips together for relative longitudinal sliding movement, a jaw to engage the side of a can depending from one end of the lower strip and a similar jaw depending from the opposite end of the upper strip, the lower strip having a longitudinal slot through which the last named jaw projects, spaced punches projecting upwardly from the strips, means mounting one punch for axial movement on one strip and means mounting the other punch on the other strip for similar movement, posts projecting upwardly adjacent the posts and secured to the corresponding strips, the upper strip having a longitudinal slot through which the post from the lower strip and the adjacent post mounting means project, handles mounted in connection with the upper ends of the posts, and means between the handles, posts and punches to depress the latter with a movement of said handles in a predetermined direction.
